UNITED STATES PATENT OFFICE

HARLOW T. STOKES, OF BROOKLYN, NEW YORK, ASSIGNOR TO INTERNATIONAL FIRE EQUIPMENT CORPORATION, OF WEST NEW BRIGHTON, NEW YORK, A CORPORATION OF DELAWARE

FIRE EXTINGUISHER

Application filed October 8, 1929. Serial No. 398,114.

This invention relates to fire extinguishers and particularly to means for attaching fire extinguishers to a lamp standard.

The invention has for its object to provide supporting means whereby fire extinguishers can be carried by a lamp standard in such a manner that the extinguishers will be readily accessible for manual operation or will be automatically released in case of fire.

Further objects of the invention will appear from the following specification taken in connection with the drawings which form a part of this application, and in which

Fig. 1 is an elevational view showing an extinguisher support carried by a lamp standard or post;

Fig. 2 is a plan view, partly broken away, of the structure shown in Fig. 1;

Fig. 3 is an elevational view showing the back plate on which the extinguishers are mounted;

Fig. 4 is an elevational view of the front plate on the extinguisher and the automatic control means;

Fig. 5 is a sectional elevation taken substantially on line 5—5 of Fig. 4;

Fig. 6 is a fragmentary top plan view of the supporting bracket on which the extinguishers are mounted;

Fig. 7 is a top plan view of the central portion of the lamp shade frame; and

Fig. 8 is a detail sectional elevation showing the manner of connecting the extinguisher bracket and lamp shade to the central standard or post of the lamp.

The invention briefly described consists of means for supporting a plurality of fire extinguishers, preferably of the grenade type, on the central post or standard of a lamp, such as a table or floor lamp. The supporting means is so constructed that a plurality of extinguishers can be mounted thereon, the extinguishers being so positioned that they will normally be concealed from view by the lamp shade but will be readily accessible for manual operation in case of fire. The extinguishers preferably consist of frangible containers or grenades and the supports are so constructed and arranged that the frangible containers will be automatically re-

leased in case of fire and will drop and break, thus releasing the fire extinguishing fluid.

Further details of the invention will appear from the following description.

In the embodiment of the invention illustrated in Figs. 1 and 2 of the drawings, there is shown a central post or standard 10 of a lamp. The upper end of the post 10 has a casing 11 secured thereto and conduits 12 and 13 extend laterally and downwardly from the casing and receive the lamp sockets 14. The wires for the lamp may extend in the usual manner upwardly through the post and laterally through the conduits 12 and 13.

A lamp shade 20 of any suitable form or shape is mounted on the standard and in the embodiment of the invention shown, the shade is carried by a ring 21, which in turn is carried by wires 22, 23, 24 and 25, which are secured at their inner ends to a flat disk or washer 26. In the usual construction the ends of the wires extend downwardly through radially disposed holes 27 formed in the washer and are bent back against the under surface of the washer.

The fire extinguishers are carried by a bracket comprising a central portion 30 and downwardly extending legs 31 and 32. The central portion 30 has a central opening 33 for receiving a bolt 29 and has slots 34 extending radially from the opening 33 and so positioned as to receive the ends of the wires 22, 23, 24 and 25 which are bent back beneath the under surface of the washer 26. By means of the construction just described, the lamp shade will always be so positioned with reference to the bracket that the legs 31 and 32, on which the extinguishers are mounted, will be positioned between the wires 22, 23, 24 or 25 of the lamp shade. Thus the extinguisher will be readily accessible for manual operation.

In the form of the invention illustrated, each extinguisher consists of a frangible container 40 of the grenade type which is supported on a pair of curved arms 41 and 42, each arm being pivotally mounted in lugs 43 and 44 which are preferably struck up out of a back plate 45. The plate 45 is secured to one of the bracket legs 31 or 32.

The outer ends of the arms are positioned in openings 50 and 51 formed in the outer ends of a pair of metallic strips 52 and 53, which in turn are connected at their inner ends by a fusible connection 54 of soft solder or other suitable material. The outer ends of the strips 52 and 53 are positioned behind inwardly extending slots or notches 56 and 57 formed in a plate 58 and are provided with lugs 60 and 61 which extend through the notches or slots 56 and 57 and in front of the plate 58.

The arms 41 and 42 are preferably formed of resilient material and are provided with shoulders 62 and 63 which engage the front of the back plate 45. The arms are so formed that they must be compressed or pressed toward each other to receive the plate 58 and the outer ends of the strips 52 and 53 carried by the plate. In case of fire the fusible connection 54 will melt or give way and the arms 41 and 42 will spread, releasing the frangible container 40.

The manner of assembling the parts above described will be clear but may be briefly outlined as follows: The central portion 30 of the bracket may be positioned at the upper end of the standard or post 10 and the lamp shade is then positioned above the bracket, the parts being correctly located by the radial slots 34 in the central portion 30 of the bracket. The bracket and shade will then be secured to the post by the bolt 29 or in any other suitable manner. It will be obvious from the plan view in Fig. 2 that the fire extinguisher containers or grenades 40 will be readily accessible through the open top of the shade so that they can be manually used, if desired. However, in case a fire occurs when no one is present, the fusible connection 54 will give way, thus releasing the grenades which will drop and break, freeing the fire extinguishing fluid contained therein.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. In combination, a lamp standard, lamps carried thereby and extending laterally therefrom, a lamp shade frame mounted on said standard having vertical openings therethrough, a bracket mounted on said standard and having a depending portion, means on said portion for supporting a fire extinguisher container, and means for so locating the bracket relative to the lamp shade frame that the container supporting means on said bracket will be positioned below one of the

frame openings whereby access to the container may be had through one of said openings.

2. In combination, a lamp standard, lamps carried thereby and extending laterally therefrom, a lamp shade frame mounted on said standard having vertical openings therethrough, a bracket mounted on said standard and having a depending portion, means on said portion for supporting a fire extinguisher container, and coacting means on the bracket and frame for so locating the bracket relative to the lamp shade frame that the container supporting means on said bracket will be positioned below one of the frame openings whereby access to the container may be had through one of said openings.

3. In combination, a lamp standard, lamps carried thereby and extending laterally therefrom, a lamp shade frame mounted on said standard having vertical openings therethrough, a bracket mounted on said standard and having depending portions, means on said portions for supporting fire extinguisher containers, and means for so locating the bracket relative to the lamp shade frame that the container supporting means on said bracket will be positioned below one of the frame openings whereby access to the containers may be had through said openings.

HARLOW T. STOKES.
